Primary Examiner — Lakiya G Rogers*Assistant Examiner* — Carissa C Fitts(74) *Attorney, Agent, or Firm* — Michael Best & Friedrich LLP(57) **CLAIM**

I claim the ornamental design for a light, as shown and described.

DESCRIPTION

FIG. 1 is a perspective view of a light embodying the invention;

FIG. 2 is another perspective view of the light of FIG. 1;

FIG. 3 is a front view of the light of FIG. 1;

FIG. 4 is a rear view of the light of FIG. 1;

FIG. 5 is a right side view of the light of FIG. 1;

FIG. 6 is a left side view of the light of FIG. 1;

FIG. 7 is a top view of the light of FIG. 1; and,

FIG. 8 is a bottom view of the light of FIG. 1.

The elements shown in broken lines form no part of the claimed design.

1 Claim, 5 Drawing Sheets(56)
